AWNNG HOIST

Bobbie E. Troutman, Paducah, Ky.

Application May 24, 1949, Serial No. 95,019

6. Claims. (Cl. 160—81)

1

This invention relates to an awning hoist and more particularly to an electric screw hoist for raising and lowering awnings and the like.

It is an object of this invention to provide an awning raising and lowering apparatus of the kind to be more particularly described herein-after which is adapted for application to many forms and types of present awning structures and requires very little modification of the present awning structure to accommodate the application of this device.

Another object of the invention is to provide an awning hoisting mechanism of this kind which comprises electric power driven screws swingably mounted above the awning and engaging the awning frame for pivotally swinging the frame to the open or folded position, the screws being swingable outwardly upon extension of the awning and swingable inwardly to a folded position upon collapsing or folding of the awning so that the awning actuating screws will not extend beyond the awning in its folded position.

Still another object of this invention is to provide a power operated awning hoist which is simple in structure and arrangement thereby conveniently lending itself to the efficient operation and ease of installation and application to the conversion of present manually operated awning structures.

With the above and other objects in view, my invention consists in the arrangement, combination and details of construction disclosed in the drawings and specification and then more particularly pointed out in the appended claims.

In the drawings:

Figure 1 is a front elevation of an awning having an awning hoist constructed according to an embodiment of this invention.

Figure 2 is a transverse section, taken on the line 2—2 of Figure 1.

Figure 3 is a fragmentary detailed section, partly broken away, showing the connection between the electric motor and the gear driven screw, at one end of the hoist.

Figure 4 is a fragmentary side elevation, partly broken away and partly in section, showing the connection of one of the nut elements with the frame and hoist screw.

Figure 5 is a transverse section, taken on the line 5—5 of Figure 4.

Figure 6 is a wiring diagram showing the switch and electric motor for actuating the hoist.

Referring to the drawings, the numeral 10 designates generally a hoist device or electric hoist for a substantially conventional type of awning

2

11, the hoist device being operatively connected to said awning for effecting extensible and contractile movement of the awning with respect to a supporting surface or support 18. The awning 11 is formed of a fabric outer body 12 including a metal frame 14 at the lower end thereof. The fabric body 12 includes an elongated, substantially rectangular, top panel 15 and a pair of outer panels 16 which are substantially triangular in configuration. The main or outer panel 15 is formed with a plurality of apertures 16' along the upper edge thereof with which fastening hooks 17 are adapted to be engaged. The fastening hooks 17 are fixedly secured to a fixed support 18 which may be a wall or other suitable fixed supporting device. The lower edges of the end panels 16 are formed with a tubular hem 19 along the length thereof and the lower forward edge of the main center panel 15 is also formed with a longitudinal extending tubular hem 20.

The metal frame 14 which is enclosed in the hems of the fabric body 12 is substantially U-shaped in configuration having a pair of outwardly extending side arms 21 connected together at their outer ends by an elongated transverse bar 22. The inner ends of the side bars 21 are pivotally connected to brackets 24 which are fixedly secured to the fixed supporting member 18 below the connection of the upper edge of the front fabric panel 15.

The type of awning described above is substantially conventional in configuration and the hoisting mechanism 10 is particularly designed for other types of awnings formed in substantially the same manner as this awning 11.

The electric hoisting apparatus 10 includes a pair of fixed brackets 25 which are fixed to the supporting member 18 and extend outwardly therefrom. One pair of brackets 25 are fixed to the supporting member 18 at one end of the awning 11 and a second pair of similar brackets 25 are fixed on the supporting member 18 in alignment with the outer panel 16, at the other end of the awning 11. The pairs of brackets 25 are fixedly supported to the supporting member 18 above the upper connection of the awning 11, above the fastening hooks 17. Each of the brackets 25 is formed with a flat rear plate 26 which is adapted to overlie the flat outer surface of the supporting member 18 and the plate 26 is formed with apertures 27 at the opposite ends thereof to which fastening devices may be engaged for fixedly securing the brackets 25 in their selected positions. A forwardly extending, triangular web 28 is fixed to or formed integral with the rear

plate 26 of each of the brackets 25 and is formed with a bearing 29 at the extreme outer end of the triangular web 28. An elongated transverse drive shaft 30 is rotatably journaled in the bearings 29 of each of the brackets 25, and extends along the entire length of the awning 11 above the upper end thereof. The shaft 30 constitutes the main drive shaft for the awning hoist mechanism 10 and is operatively connected to an electric motor 31 which is fixed on the supporting member 18, adjacent one end of the shaft 30 outwardly beyond one end of the awning 11.

A shelf or bracket 32 is fixed on the supporting member 18 adjacent one end of the awning 11 and includes a rear flat plate 34 which is adapted to be fixed to the flat outer surface of the member 18 and a forwardly extending horizontal shelf or plate 35. The supporting bracket 32 is formed in a substantially conventional manner having fixed triangular braces 36 connected between the vertical plate 34 and the horizontal plate 35. The motor 31 is adapted to be fixedly mounted on the upper horizontal plate 35, of the bracket 32 and a suitable reduction gear casing 37 is fixed on the casing of the motor 31 or otherwise suitably mounted for connection between the motor 31 and one end of the drive shaft 30. The reduction gear mechanism 37 includes a small gear 38 fixedly mounted on the drive shaft 39 of the motor and engageable with an enlarged driven gear 40 which is fixedly connected to one end of the drive shaft 30.

A bevel gear 41 is fixed on one end of the drive shaft 30, between one pair of brackets 25 and a second, similar, bevel gear 42 is fixed on the other end of the shaft 30 between the other pair of brackets 25. A gear housing 44 or box is pivotally engaged about the shaft 30, between each of the brackets 25 at the opposite ends of the shaft. Each of the gear boxes 44 includes a pair of side walls 45 and 46 formed with bearings 47 and 48 respectively rotatably engaging the drive shaft 30. The side walls 45 and 46, of each of the gear boxes 44 are connected together by front, rear and top walls for enclosing the gears 41 and 42. As thus pivotally mounted on the opposite ends of the drive shaft 30, the gear boxes 44 are substantially free for rotation between the supporting brackets 25.

An elongated screw 48 is rotatably journaled at one end in the front wall of one of the gear casings 44 and extends downwardly and outwardly therefrom. A beveled gear 49 is fixed on the inner end of the shaft 48 and meshes with the beveled gear 41 for rotating the screw 48. The lower end of the screw 48 is threadably engaged in a nut element 50 which is pivotally connected to one end of the transverse frame bar 22. A second elongated screw 51 is rotatably journaled in the front wall of the other gear box 44 and has fixed on its inner end a gear 52 for meshing engagement with the gear 42. The screw 51 is threadably engaged with the other nut element 54 which is pivotally mounted on the other end of the transverse frame bar 22.

Each of the nut elements 50 and 54 is formed with a cylindrical sleeve body 55 having a central threaded bore 56 internally thereof. The screws 48 and 51 are adapted to be threadably engaged through the sleeves 55 in threaded engagement with the internal bore 56 thereof. An inwardly extending gear 57 is fixed to, or preferably formed integrally with one side of the sleeve body 55 to be pivotally or swingably connected

to the extreme outer end of one of the side bars 21 of the frame 14. Each of the side bars 21, of the frame 14, is formed with a bifurcated outer end which includes a pair of transversely spaced 5 apart, forwardly extending side arms 58 and 59 having aligned bearings or apertures 60 and 61 for rotatably journaling the end of the transverse frame bar 22. The inwardly extending gear 57, of each of the nut elements 50 and 54 is formed 10 with a central aperture therein through which the transverse frame bar 22 is adapted to be rotatably engaged. The inwardly extending gear 57 is adapted to be positioned between the side arms 58 and 59 of the outer end of one of the side arms 15 21 for pivotally or swingably connecting the nut elements on the frame 14.

A suitable electric circuit 62 is adapted to be connected to the electric motor 31 for actuating the hoisting mechanism 10 and is connected to a conventional source of electric supply 64. The electrical circuit 62 between the source of electric supply 64 and the motor 31 includes a switch 65 for connecting the motor 31 for selected reverse rotation. In other words by suitable manipulation of the switch 65, between the source of electric supply 64 and the motor 31, the motor shaft 39 may be rotated in a selected direction for selectively raising or lowering the awning 11.

In the use and operation of the awning hoist 10, 30 the awning hoist is mounted in the manner described above, and upon actuation of the motor 31, when the awning is lowered as shown in Figures 1 and 2 of the drawings the connection of the switch for rotating the motor shaft 31 in one direction will effect the simultaneous rotation of both of the screws 48 and 51 in their respective nut elements 50 and 54 to effect the pivoting movement of the frame 14 upwardly about its pivot brackets 24 for collapsing or raising the 35 awning 11. As the drive shaft 31 is positioned outwardly beyond the pivot connections 24, in the fully folded position of the awning 11 the frame 21 will be positioned vertically in substantially overlying position relative to the supporting base 18 and the screws 48 and 51 will substantially overlie, on the outer side, the side bars 21 of the frame 14 so that the screws 48 and 51 will be folded inwardly relative to the awning 11 in its 40 folded or collapsed position.

As the switch 15 is positioned for rotating the motor shaft 39 in the opposite direction for lowering the awning 11, the drive shaft 30 will be rotated in the opposite direction for reversely rotating the screws 48 and 51 for lowering the awning frame 14 about its respective pivot. As the nut elements 50 and 54 are lowered along the length of the screws 48 and 51, the gear housing 44 will be rocked outwardly about the drive shaft 30 and the nut elements 50 and 54 will be rocked inwardly and upwardly relative to the transverse frame bar 22, to a position shown in Figure 2 of the drawings.

I do not mean to confine myself to the exact details of construction herein disclosed, but claim all variations falling within the purview of the appended claims.

What I claim is:

1. An awning hoist for an awning having a frame pivotally mounted on a fixed support and including a transverse outer bar comprising a pair of spaced apart nut elements pivoted on said outer bar, a pair of gear housings pivoted on said support, a rotatable screw extending from each of said gear housings and engaging the respective nut elements; and electrically actuatable

gear means in said housings for rotating said screws for raising and lowering said awning.

2. An awning hoist for an awning having a frame swingably mounted on a fixed support comprising a pair of spaced apart nut elements pivoted on said frame, a pair of pivot brackets fixed on said support and extending outwardly beyond the pivotal connection of said frame, a rotatable shaft journaled in said brackets, a pair of spaced apart gear boxes pivotally mounted on said shaft, a screw rotatable in each of said boxes extending therefrom and engaging the respective nut elements, gear means in each of said boxes connected between said shaft and said screws, and electric means connected to said shaft for raising and lowering said awning.

3. An awning hoist for an awning having a frame swingably mounted on a fixed support comprising a pair of spaced apart nut elements pivoted on said frame, a pair of pivot brackets fixed on said support and extending outwardly beyond the pivotal connection of said frame, a rotatable shaft journaled in said brackets, a pair of spaced apart gear boxes pivotally mounted on said shaft, a screw rotatable in each of said boxes extending therefrom and engaging the respective nut elements, gear means in each of said boxes connected between said shaft and said screws, electric means connected to said shaft for raising and lowering said awning, said screws being respectively pivoted with said boxes and overlying said frame in the folded, raised position of said awning.

4. The combination with an awning including a horizontally disposed frame having one end pivotally connected to a supporting surface for movement from a horizontal position to a vertical position, a fabric body superimposed upon said frame and secured to the latter, the upper end of the said body being pivotally connected to the supporting surface above and spaced from the pivotal connection of said frame, a transversely disposed bar carried by the other end of said frame and secured to the lower end of said body, of a hoist device operatively connected to said frame and said supporting surface for effecting extensible and contractile movement of said awning with respect to said supporting surface, said device comprising a horizontally disposed shaft extending transversely of said frame positioned above and spaced from the upper end of said body and rotatably supported on said supporting surface, a pair of spaced projecting nut elements arranged above the swinging end of said frame and pivotally secured to the latter, and a pair of screws arranged transversely of and spaced above said body and each having one end in threaded engagement with the nut element adjacent thereto, and having the other end pivotally and rotatably connected to said shaft.

5. The combination with an awning including a horizontally disposed frame having one end pivotally connected to a supporting surface for movement from a horizontal position to a vertical position, a fabric body superimposed upon said frame and secured to the latter, the upper end of said body being pivotally connected to the supporting surface above and spaced from the

pivotal connection of said frame, a transversely disposed bar carried by the other end of said frame and secured to the lower end of said body, of a hoist device operatively connected to said frame and said supporting surface for effecting extensible and contractile movement of said awning with respect to said supporting surface, said device comprising a horizontally disposed shaft extending transversely of said frame positioned above and spaced from the upper end of said body and rotatably supported on said supporting surface, a pair of spaced projecting nut elements arranged along the swinging end of said frame and pivotally secured to the latter, a pair of screws arranged transversely of and spaced above said body and each having one end in threaded engagement with the nut element adjacent thereto and having the other end pivotally and rotatably connected to said shaft, and electrically actuable gear means operatively connected to said shaft for effecting extensible and contractile movement of said frame.

6. The combination with an awning including a horizontally disposed frame having one end pivotally connected to a supporting surface for movement from a horizontal position to a vertical position, a fabric body superimposed upon said frame and secured to the latter, the upper end of said body being pivotally connected to the supporting surface above and spaced from the pivotal connection of said frame, a transversely disposed bar carried by the other end of said frame and secured to the lower end of said body, of a hoist device operatively connected to said frame and said supporting surface for effecting extensible and contractile movement of said awning with respect to said supporting surface, said device comprising a horizontally disposed shaft extending transversely of said frame positioned above and spaced from the upper end of said body and rotatably supported on said supporting surface, a pair of spaced projecting nut elements arranged along the swinging end of said frame and pivotally secured to the latter, a pair of screws arranged transversely of and spaced above said body and each having one end in threaded engagement with the nut element adjacent thereto and having the other end pivotally and rotatably connected to said shaft, a housing enclosing the other end of each of said screws and rotatably mounted on said shaft, a gear on said other end of each of said screws, and a second gear on the portions of said shaft within each of said housings and in meshing engagement with the gear on said screws adjacent thereto.

BOBBIE E. TROUTMAN.
